COMBINED PERFUME BOTTLE AND STAND

Adam Zayzman, New York, N. Y.

Application February 28, 1950, Serial No. 8,203

Term of patent 3½ years

(Cl. D58—6)

To all whom it may concern:

Be it known that I, Adam Zayzman, a citizen of Uruguay, residing at New York city, in the county of New York and State of New York, have invented a new, original, and ornamental Design for a Combined Perfume Bottle and Stand, of which the following is a specification, reference being had to the accompanying drawing, forming part thereof.

In the drawing:

Fig. 1 is a side elevational view of a combined perfume bottle and stand, showing my new design; Fig. 2 is a front elevational view thereof; and Fig. 3 is a top plan view thereof.

I claim:

The ornamental design for a combined perfume bottle and stand, substantially as shown.

ADAM ZAYDMAN.
